UNITED STATES PATENT OFFICE

JOHN JAMES SHERIDAN, OF PHILADELPHIA, PENNSYLVANIA

DESIGN FOR A CABINET

Application filed December 24, 1931. Serial No. 42,189. Term of patent 14 years.

To all whom it may concern:

Be it known that I, JOHN J. SHERIDAN, a citizen of the United States, residing at Philadelphia, in the county of Philadelphia and State of Pennsylvania, have invented a new, original, and ornamental Design for Cabinets, of which the following is a specification, reference being had to the accompanying drawings, forming part thereof.

showing my new design, the same being closed.

Figure 2 is a similar view at a different angle and with the doors of the cabinet shown in the open position.

I claim:

The ornamental design for a cabinet, as shown.

JOHN JAMES SHERIDAN.
